UNITED STATES PATENT OFFICE.

SIMON EISENSTEIN, OF KIEW, RUSSIA.

RECEIVER FOR WIRELESS TELEGRAPHY AND TELEPHONY.

No. 931,586.

Specification of Letters Patent. Patented Aug. 17, 1909.

Application filed March 27, 1908. Serial No. 423,638.

To all whom it may concern:

Be it known that I, SIMON EISENSTEIN, a subject of the Czar of Russia, residing in Kiew, in the Empire of Russia, have invented certain new and useful Improvements in Receivers for Wireless Telegraphy and Telephony, of which the following is a specification.

The present invention has for its object a method of electrical connection for diminishing the damping in the resonant circuit of the receiver by means of which it is also possible to receive undamped oscillations by means of a telephone receiver. Poulsen has already suggested (see *Elektrotechnische Zeitschrift*, Berlin, No. 45, Nov. 8, 1906, especially pp. 1042 and 1043 and Figs. 29-32) the employment of what is termed a "ticker" for the purpose of diminishing the damping and for adapting telephone detectors as receivers, the detector only being switched in intermittently when the amplitude in the resonant circuit of the receiver has already attained a high value by resonance, which is relatively readily effected, because, during the increase of the amplitude, the resonant circuit is given a slight self-damping by cutting out the detector. The ticker presents the defect, however, that when the detector is cut out subsidiary vibrations are produced which exert an influence upon the sensitivity of the receiver. The present invention aims at the same object but no make or break place is provided so that the formation of subsidiary vibrations is entirely avoided, this object being attained owing to the fact that the secondary coil of the receiver transformer arranged in the resonant circuit of the receiver is brought into the field of the primary coil for a brief moment only, so that it is only during the period in which the secondary coil is not located in the field of the primary coil that the amplitude is able to increase with diminished damping.

The invention is diagrammatically illustrated in the accompanying drawing.

Figure 1 illustrates the general arrangement of the apparatus, and Figs. 2 and 3 show different ways of arranging the receiving transformer coils with respect to each other.

The antenna 1 is connected with a resonant circuit 2 provided in the usual manner with the receiver transformer or resonator 3, the capacity 4 and the coupling coil 5. The sec-

ondary coil 3' of the receiver transformer is connected with the detector 6 and in parallel with a capacity 7. If the secondary winding of the receiver transformer were not provided, the system would have a very slight damping, which is increased by the interpolation of the secondary coil with the detector.

Now as already stated, in accordance with the present invention the secondary coil 3' of the receiver transformer is brought into the field of the primary coil for a brief moment only, so that for the rest of the time with a diminished damping an increase of the amplitude can take place.

By alternating the switching in and cutting out of the secondary coil in the field of the primary winding, it is possible to receive messages by the telephone. The secondary coil may of course be switched in and out in different ways, for example by the oscillation of the secondary coil or by an eccentric circular movement in front of the primary coil or finally by rotating the planes of the coils.

Two examples of the arrangement for varying the relative positions of the primary and secondary transformer coils are shown in Figs. 2 and 3. In Fig. 2, 3 represents the coil-like primary member of the resonant circuit. The secondary coil 3', which is connected with the detector, is rotatable at a, so that the coil can turn within the convolutions of the primary member 3 on the axis a. The secondary member 3' is located in this arrangement, during its rotation only, in the magnetic field of the primary coil when the windings of both coils are parallel with each other, but when the same cross each other, or are arranged at an angle to each other (as shown in Fig. 2), no effect is present, or the same is at least considerably diminished.

In the form shown in Fig. 3, the secondary member 3' is rotatable, by means of a suitable supporting frame, about the point b, and is either moved by an entire circular motion around the point b or by to and fro oscillation temporarily placed opposite the primary member 3, as shown. It is only when the position shown in the drawing is reached that the intended effect is obtained.

As in accordance with the present invention no make and break place is provided, as is necessary with Poulsen's known ticker device, the subsidiary vibrations thereby produced are avoided in the present arrangement.

Having thus described my invention, I claim as new and desire to secure by Letters Patent:

1. In apparatus for wireless telegraphy, the combination, with a resonant circuit and a primary receiving transformer coil in said circuit, of a secondary transformer coil arranged to be continuously moved with respect to the primary coil and connected with 10 a detector.
2. In apparatus for wireless telegraphy, the combination, with a resonant circuit and a primary receiving transformer coil in said

circuit, of a secondary transformer coil outside the circuit arranged to be continuously 15 moved into and out of the field of the primary coil, and a detector connected with said secondary coil.

In testimony, that I claim the foregoing as my invention, I have signed my name in 20 presence of two subscribing witnesses.

SIMON EISENSTEIN.
